UNITED STATES PATENT OFFICE.

LOUIS F. ROBERTSON, OF NEW YORK, N. Y.

IMPROVEMENT IN COMPOUNDS FOR BATING HIDES AND SKINS.

Specification forming part of Letters Patent No. 110,161, dated December 13, 1870.

To all whom it may concern:

Be it known that I, LOUIS F. ROBERTSON, of the city, county, and State of New York, have invented a new and Improved Compound for Bating Hides and Skins; and I do hereby declare the following to be a full, clear, and exact description thereof, which will enable those skilled in the art to make and use the same.

This invention relates to an improvement on a compound for bathing all sorts of hides and skins for upper and harness leather, and also sheep and goat skins, as described in Letters Patent No. 87,202, granted to me February 23, 1869, said compound being made of water, molasses, sawdust, and urine, or of urine, molasses, blood, and water.

The compound which forms the subject-matter of my present application for a patent consists of water, sawdust, and ammonia, with or without blood and urine. These ingredients are mixed together in about the following proportions: sawdust, one and one-half bushel; blood, three gallons; urine, two and one-half gallons; water, one hundred and fifty gallons; ammonia, one pound; or, if blood and urine are dispensed with, the proportions are about as follows: sawdust, two bushels; water, one hundred gallons; ammonia, two pounds. These proportions will, however, undergo slight modifications according to the condition of the water and the season, and for various kinds of hides and skins the proportion must be increased or diminished.

When blood is used, it can either be employed in a fresh state or the blood may be dried and preserved until it is to be used, when it is dissolved in water, the quantity of dried

blood employed in this case being equivalent to the quantity of fresh blood as above stated.

The peculiar advantages of my bathing compound, when compared with the bates heretofore used, may be enumerated as follows: First, by the application of my compound any common workman is enabled to perform the bathing process without danger of injuring or spoiling the stock, which often happens by the old bathing process, even if an experienced workman has charge of the labor; second, the cost of the process of bathing with my compound is only one-third of that of the old process; third, the process of bathing, when carried on with my compound, is not subjected to the influence of thunder-storms, whereby the stock subjected to the old bathing process is frequently damaged or spoiled.

What I claim as new, and desire to secure by Letters Patent, is—

1. A compound for bathing hides and skins, made of sawdust, water, and ammonia mixed together, substantially in the manner herein set forth.
2. A compound for bathing hides and skins, made of blood and ammonia.
3. A compound for bathing hides and skins, made of blood, sawdust, and ammonia.
4. A compound for bathing hides and skins, made of sawdust, blood, urine, water, and ammonia mixed together, substantially in the manner herein specified.

This specification signed by me this 20th day of September, 1870.

L. F. ROBERTSON.
